UNITED STATES PATENT OFFICE

139,417

DESIGN FOR A COMBINED CIGARETTE, MATCH, BILL, AND COIN FOLD

Barbara Jean Glafke, New York, N. Y.

Application December 30, 1943, Serial No. 112,126

Term of patent 14 years

(Cl. D85—2)

To all whom it may concern:

Be it known that I, Barbara Jean Glafke, a citizen of the United States, residing in New York, in the county of New York and State of New York, have invented a new, original, and ornamental Design for a Combined Cigarette, Match, Bill, and Coin Fold, of which the following is a specification, reference being had to the accompanying drawing, forming part thereof.

In the drawing—

Fig. 1 is a front perspective view of a combined cigarette, match, bill and coin fold, in open position, showing my new design.

Fig. 2 is a side view of the fold, in closed position.

Fig. 3 is a rear perspective view showing the fold in closed position.

I claim:

The ornamental design for a combined cigarette, match, bill, and coin fold, as shown.

BARBARA JEAN GLAFKE.
